MULTIPLE FLOW COLUMN

Daniel C. Lockwood, South Pasadena, Calif., assignor to C. F. Braun & Co., Alhambra, Calif., a corporation of California

Application March 22, 1948, Serial No. 16,302

1 Claim. (Cl. 261—114)

1

This invention relates to liquid-vapor contact apparatus and is particularly directed to improvements in vessels or columns of the type used for contacting an ascending column of vapor with a descending stream of liquid. Such vessels are commonly employed in connection with chemical processing apparatus. This invention will be described in connection with a vacuum flasher column of the type now employed in the refining of petroleum and petroleum products, but it is to be understood that the invention is not limited to this particular embodiment or use.

Conventional columns employing vertically spaced staggered splash decks or vertically spaced circular baffles of the disk and doughnut type are well known in the art, but only a single liquid curtain is provided between adjacent splash decks or baffles. Such arrangements have been found to be satisfactory for small and medium diameter vessels, but on very large diameter vessels the required vertical spacing between decks or baffles is so great that the overall height of the column becomes excessive. The vertical spacing is determined by the required areas for proper flow of the ascending vapor.

In accordance with this invention a multiple flow of liquid in a plurality of separate liquid curtains is provided between adjacent levels of splash decks or baffles, with the result that sufficient passage area for ascending vapor is provided to permit much closer spacing of the splash decks or baffles, and therefore the overall height of the column may be substantially reduced.

Accordingly, it is the principal object of this invention to provide a novel form of liquid-vapor contact vessel of high efficiency and substantially reduced overall height.

Another object is to provide a new and improved splash deck assembly adapted to produce a plurality of liquid curtains between adjacent levels of splash decks.

Other objects and advantages will appear hereinafter.

In the drawings, Figures 1 to 4 illustrate diagrammatically conventional forms of liquid-vapor contact apparatus. Figure 1 is a sectional elevation showing a conventional splash deck arrangement. Figure 2 is a sectional view taken substantially on lines 2—2 as shown in Figure 1.

Figure 3 is a sectional elevation showing a conventional disk and doughnut baffle arrangement.

Figure 4 is a sectional plan view taken substantially on lines 4—4 as shown in Figure 3.

Figure 5 is a diagrammatical sectional elevation showing a column structure embodying my

2

invention and employing vertically spaced splash decks.

Figure 6 is a sectional plan view taken substantially on the lines 6—6 as shown in Figure 5.

Figure 7 is a view similar to Figure 6 taken substantially on lines 7—7 as shown in Figure 5.

Figure 8 is a diagrammatical sectional elevation of a modified form of column structure embodying my invention.

Figure 9 is a sectional plan view taken substantially on lines 9—9 as shown in Figure 8.

Figure 10 is a view similar to Figure 9 taken substantially on lines 10—10 as shown in Figure 8.

Figure 11 is a sectional elevation of a portion of a column structure and showing a preferred embodiment of my invention.

Figure 12 is a sectional plan view taken substantially on lines 12—12 as shown in Figure 11.

Figure 13 is a view similar to Figure 12 taken substantially on lines 13—13 as shown in Figure 11.

Figure 14 is a sectional plan view taken substantially on lines 14—14 as shown in Figure 11.

Figure 15 is a transverse sectional elevation showing details of construction of a preferred form of splash deck embodying my invention.

Figure 16 is a transverse sectional view showing details of construction of another form of splash deck embodying my invention.

Referring to the drawings, the conventional forms of liquid-vapor contact columns shown in Figures 1 to 4 employ vertically spaced baffles over which a flow of liquid occurs. As the liquid falls by gravity from a baffle on one level to a baffle at a lower level a liquid curtain is provided, and ascending vapors are passed through these liquid curtains in order to achieve the desired liquid-vapor contact.

As shown in Figure 1 the shell 10 provides a closed vessel having an outlet 11 for vapor at its upper end, an outlet 12 for liquid at its lower end, an inlet 13 for liquid near its upper end, and an inlet 14 for a vapor liquid mixture. Vertically spaced splash decks 15, 16 and 17 are mounted within the shell 10 in staggered relation. Liquid admitted through the inlet 13 flows over the outer edge 18 of the upper splash deck 15 and falls in the form of a liquid curtain 19 to the next lower splash deck 16. Similarly, liquid on the splash deck 16 falls over its outer edge 20 in the form of a liquid curtain 21 down to the lower splash deck 17.

Ascending vapors admitted into the shell by way of the inlet 14 must pass

through liquid curtains 21 and 19 in order to reach the vapor outlet 11.

If desired, a liquid collector trough 22 may be mounted within the shell at a location to receive the liquid falling from the lower splash deck 17. Liquid in the trough may be withdrawn through piping (not shown) and if desired may be recirculated through the upper liquid inlet 13. The vertical spacing between the splash decks is proportioned with respect to the width of the horizontal opening at each level so that the passage areas for vapor remain substantially equal, or so that the passage areas are proportioned in a predetermined relationship. Thus the area of the liquid curtains 19 and 21 is made substantially equal to the area of the horizontal openings between the edges 18 and 20 and the adjacent wall of the column 10. The path of the ascending vapors is diagrammatically illustrated by the arrows 23.

In the conventional apparatus shown in Figure 3 the shell 10a provides a closed vessel having outlets 11a, 12a, and inlets 13a, 14a, similar to those just described in connection with Figure 1. Instead of segment shaped staggered splash decks, baffles in the form of disks 25 and doughnuts 26 and 27 may be provided in vertically spaced relationship. These disks and doughnuts may be supported in any conventional manner as, for instance, by brackets fastened to the shell wall. The disks 25 are preferably circular and imperforate, while the doughnuts are annular in form and are provided with a central opening. Liquid admitted into the shell via the inlet 13a falls from the doughnut 26 in the form of a circular liquid curtain 28 and impinges on the disk 25. The liquid then falls from the outer perimeter on the disk in the form of a circular liquid curtain 29. Vapors admitted into the shell 10a via the inlet 14a must pass through the circular liquid curtains 29 and 28 in order to reach the vapor outlet 11a provided at the top of the shell 10a.

If desired a collector ring 30 may be supported within the shell and positioned under the circular liquid curtain 31 falling from the central aperture in the doughnut 27. Piping (not shown) may be provided for withdrawing the liquid from the shell 10a, and if desired such liquid may be recirculated through the inlet 13a. The vertical spacing between disks and doughnuts is proportioned with respect to the areas of the annular openings around the disks and to the central openings in the doughnuts in a manner such that the passage areas for ascending vapors are maintained substantially equal. The path of the ascending vapors is diagrammatically illustrated by the arrows 32.

It will be noted that in the conventional type columns shown in Figures 1 and 3 a single sheet of liquid or liquid curtain is present at each level through which ascending vapors may pass. Such arrangements have been found to be satisfactory for small and medium diameter vessels, but on large vessels the vertical spacing between splash decks or between baffles is so large that the overall height of the column becomes excessive. The use of catalytic cracking units in the refining of petroleum requires very large amounts of feed stock of the type provided by liquid-vapor contact columns of the type disclosed herein. The required capacities are so large that the cost of conventional columns of the type shown in Figures 1 and 3 becomes prohibitive.

In accordance with my invention, I provide

a multiple or divided flow of liquid in a plurality of separate liquid curtains between adjacent levels of splash decks or baffles, and in this manner secure sufficient passage area for ascending vapors while utilizing much closer spacing of the splash decks or baffles. The overall height of the column may be thus substantially reduced. As illustrated diagrammatically in the preferred embodiment shown in Figures 5 to 7, I provide a plurality of splash decks at each level within a column, and the vertical spacing between levels is substantially reduced since multiple passages for ascending vapors and multiple liquid curtains are provided between each level. Thus, the shell 40 provides a closed vessel having a vapor outlet 41 near its upper end, a liquid outlet 42 near its lower end, a liquid inlet 43, and an inlet 44 for vapor liquid mixture.

Parallel splash decks 45 and 46 extend transversely across the column and define a horizontal space 47 therebetween and horizontal spaces 48 and 49 between the splash decks and the walls of the column 40. Four separate spaced liquid curtains 50 are formed along the parallel edges of the splash decks 45 and 46. Liquid is directed onto the upper surfaces of the splash decks 45 and 46 from distributor pipes 51 and 52 supplied from the common inlet 43. The liquid curtains 50 fall on three transversely extending splash decks 53, 54 and 55 as shown in Figure 7.

Spaces 56 and 57 are defined between parallel horizontal edges of the splash decks 53, 54 and 55. Four separate parallel liquid curtains 58 extend downwardly from the parallel edges of the splash decks 53, 54 and 55 and are intercepted by the parallel spaced splash decks 59 and 60. The splash decks 59 and 60 are similar to the splash decks 45 and 46 and accordingly need not be further described. The liquid curtains 61 falling from the splash decks 59 and 60 may be intercepted by collector troughs 62, 63 and 64 if desired, and the liquid may be withdrawn from the shell through piping (not shown). The liquid may be recirculated through the inlet 43. It will be observed that the downward flow of liquid is divided on the upper surface of the splash decks 45 and 46, and thereafter multiple liquid curtains are provided between adjacent levels. These multiple curtains provide sufficient passage area to enable the vertical spacing between levels to be substantially reduced without impairing the efficiency of the column.

In the modified form of my invention illustrated in Figures 8 to 10, disk and doughnut baffles are used instead of the splash deck arrangement shown in Figures 5 to 7. The shell 40a, outlets 41a and 42a, and inlets 43a and 44a, together with the distributor pipes 51a and 52a, may be substantially the same as those described in connection with Figures 5 to 7. Liquid directed against the upper surface of the annular ring or doughnut 70 flows downwardly from the inner and outer peripheries thereof in the form of two circular concentric liquid curtains 71 and 72. These liquid curtains impinge on doughnut 73 and the central disk 74. Concentric liquid curtains 75 and 76 extend downwardly from the outer periphery of the disk 74 and the inner opening in the doughnut 73 respectively. An annular ring or doughnut 77 intercepts both of the concentric liquid curtains 75 and 76 in a manner similar to that described above; concentric circular liquid curtains 78 and 79 extend downwardly from the central opening in the doughnut 77 and its outer periphery respectively.

5

The liquid falling from the doughnut 77 may be collected in the collector rings 80 and 81 if desired, and the liquid may be withdrawn from the vessel through piping (not shown). If desired, such liquid may be recirculated through inlet 43a. It will be observed that multiple paths for vapor are provided through the pair of concentric circular liquid curtains provided between each level of baffles. Accordingly, the vertical spacing between baffles may be reduced without impairing the efficiency of the column, and the overall height of the column may be reduced.

In Figures 11 to 16 I have shown a preferred embodiment of my invention in considerable detail. Splash decks are illustrated instead of disks and doughnuts, since it has been found that the contact areas for liquid and vapor can be kept more uniform in this manner. Distributor pipes 90 may be supplied with liquid from a single or separate inlets (not shown), and these distributor pipes 90 extend horizontally across the interior of the column shell 91 above a distributor trough 92 provided on each of the splash decks generally designated 93 and 94. The splash decks 93 and 94 extend transversely across the shell in parallel relation and define a space 95 between their adjacent parallel edges and spaces 96 and 97 between the shorter edges of the disks and the interior of the wall of the shell 91. The distributor troughs 92 each include a longitudinal horizontal plate 98 having upturned parallel edges 99. Upright stiffener plates 100 extend between the edges 99 and are spaced at intervals along the horizontal plate 98. Upright strips 101 are bolted or otherwise attached to the upturned edges 99 and are notched on their upper longitudinal edge 102 to provide a weir. These weir plates 101 function to divide the liquid flowing from the distributor trough 92 into two separate streams. These streams flow in opposite directions over the inclined deck plates 103 and 104. An upturned lip 105 and 106 is provided along the outer edge of each of the inclined deck plates 103 and 104 respectively.

A series of apertures 107 and 108 may be formed along the outer edge of each inclined deck plate adjacent its upturned lip. Liquid flows downwardly through said apertures 107 and 108 in the form of a "rain" to provide liquid curtains 109 and 110 extending downwardly from the edges of the splash deck 93, and to provide liquid curtains 111 and 112 flowing downwardly from the edges of the splash deck 94. Suitable structure 113 may be provided for supporting the distributor pipes 90 on the splash decks 93 and 94.

Supporting structure for the splash decks 93 and 94 is provided within the column 91, and this structure is positioned and proportioned so that a minimum of restriction is imposed upon the upward flow of vapors from the spaces between the splash decks 114, 115 and 116 on the next lower level. As shown in Figures 12 and 15 this supporting structure preferably comprises a central beam 117 which may be bent from a single sheet to form a rectangular box section and joined to the horizontal plate 98 by any convenient means, such as for example spot welding. The central beam 117 extends longitudinally under the horizontal deck plate 98 and may be bolted to end supports 118 fixed within the wall of the shell 91. Flanges 119 may be welded to the beam 117 at spaced intervals, and cantilever trusses 120 may be bolted to these flanges 119 and extend outwardly under the in-

6

clined splash decks 103 and 104 to provide a support therefor. It will be observed that the supporting structure for the splash decks 93 and 94 is positioned remotely from the upturned edges 105 and 106 and from the liquid curtains extending downwardly therefrom in order that the effective passage areas through the liquid curtains may not be decreased.

In order to provide a substantially equal liquid-vapor contact, the widths of the splash decks 93 and 94 are so proportioned with respect to the widths of the openings 95, 96 and 97 that the end area of the openings 96 and 97 bear a relation to the area of the opening 95 which is equal to the relation between the length of the short side 106 of the splash decks and the length of the long side 105.

The inclined deck plates 103 may be bolted to the cantilever supports 120. The construction is such that the beam 117, cantilever supports 120, inclined splash decks 103 and 104, and associated parts may be withdrawn from the column when desired for the purposes of cleaning or inspection. The openings in the column ends 25 are made sufficiently large to accommodate the largest single removable piece.

The four liquid curtains 109, 110, 111 and 112 extending downwardly from the splash decks 93 and 94 impinge on the splash decks 114, 115 and 30 116. The splash deck 115 may be substantially identical to the splash decks 93 and 94 described above, with the exception that the weir plates 101 are omitted. The side splash decks 114 and 116 are each bolted to an annular horizontal ring 150 welded to the interior of the shell 91. Stiffener ribs 151 are bolted to support plates 152 secured to the interior of the shell 91 at circumferentially spaced intervals. The deck plates 122 may be positioned substantially horizontally and provided with an upturned lip 121. It will be observed that the splash decks 114 and 116 are each comprised of a plurality of individual sections, each having an upturned lip 121 and a pair of spaced side stiffeners 151. The lip 121 extends 45 inwardly under the upper splash deck 93, 94, and a series of apertures 122a may be provided in the deck plates 122 adjacent the lip 121. Liquid on the splash deck passes through the apertures 122a in the form of a rain or liquid curtain 123, 50 124.

The liquid curtains 123 and 124 falling from the side splash decks 114 and 116, and the liquid curtains 125 and 126 falling from the splash deck 115 impinge on the splash decks 127 and 128 which are substantially identical to the splash decks 93 and 94, except that the weir plates 101 are omitted. Accordingly, liquid on the splash decks 127 and 128 falls in four separate liquid curtains 129, 130, 131 and 132. The liquid in 60 the latter said curtains may be collected within the shell 91 if desired and recirculated into the distributor pipes 90. As shown in Figures 11 and 14, side collector basins 133 and 134 are provided for intercepting the liquid curtains 129 and 132. A central collector pan 135 receives the liquid 65 from the curtains 130 and 131. Any convenient or desired construction may be employed for such collector basins, and such preferably includes removable bottoms 136 mounted on transversely extending beams 137. The beams 137 may be bolted to end supports 138 fixed within the shell 91. Suitable piping (not shown) may be provided for withdrawing liquid from the shell 91.

The upper edges of the upturned lips 105 and 75 106 of the splash decks 93, 94, 115, 127 and 128

may be notched if desired along their entire length in order to form weirs for uniform distribution of fluid along the length of the splash decks. Should the apertures 107 and 108 adjacent the lips become plugged and cease to function properly, the notches along the upper edges of the lips function to provide liquid curtains. In a similar manner the upturned lips 121 on the side splash decks 114 and 116 may be also notched along their upper length to provide weirs. Failure of the apertures 122 to function properly would then permit fluid to flow over the weirs in uniform curtain.

The deck plates 103 and 104 as shown in Figure 15 are oppositely inclined to direct liquid through the apertures 107 and 108 or over the lips 105 and 106. The inclination of the deck plates 103 and 104 is highly desirable for columns which are to operate at relatively high temperature, since in such cases it is desirable to keep the liquid moving at a relatively high flow rate and to avoid any sluggishness in flow. By this means objectionable coking on the trays is prevented or minimized. For columns which operate at lower temperatures, however, the coking problem is not troublesome, and accordingly, the decks 103 and 104 may be placed substantially horizontal if desired.

Having fully described my invention, it is to be understood that I do not wish to be limited to the details herein set forth, but my invention is of the full scope of the appended claim.

I claim:

In a vessel of the class described for contacting an ascending column of vapor with a descending stream of liquid, the combination of: a shell, a first transverse splash deck including a horizontal beam extending transversely across the shell and being removably fastened to the walls thereof, a distributor trough mounted along the upper surface of said beam, cantilever support plates fastened to and extending laterally from both sides of said beam at spaced intervals therealong, said

5 cantilever plates being tapered with the widest end fastened to said beam, a pair of oppositely inclined deck plates carried on and overlying said cantilever plates and sloping downwardly away from said beam, inner edges of said deck plates underlying the outer edges of said trough, the deck plates each being provided with an upturned lip along its lower edge, a second transverse splash deck similar to said first splash deck positioned below said first splash deck and spaced laterally therefrom so that one of said lips of the upper splash deck overlies one of the deck plates of said second splash deck, a third transverse splash deck similar to said first splash deck positioned similarly to said second splash deck so that the other of said lips of said first splash deck overlies one of the deck plates of said third splash deck, said one of the lips on said first splash deck cooperating with the lip on said one deck plate of said second splash deck to define the edges of a first passageway for ascending vapor, the other of said lips on said first splash deck cooperating with the lip on said one deck plate on said third splash deck to define the edges of a second passageway for ascending vapor, said beam associated with said first splash deck being remote from the edges of both the first and second passageways to provide maximum unobstructed passage area for ascending vapor.

DANIEL C. LOCKWOOD.
